POWER BOAT

John Robert McMullen, Galena, Ill.

Application February 27, 1936, Serial No. 66,114

3 Claims. (Cl. 115—39)

My invention relates generally to self-propelled boats, and particularly to a power boat suitable for passenger and cargo service, and for high speed navigation, and an important object of the invention is to provide a simple and well balanced boat of this character having an inverted keel forming a water tunnel in which propelling means works.

Another important object of my invention is to provide a stable and easily maneuvered power boat of the character indicated which is strong and rugged while being comparatively light in weight.

Another important object of my invention is to provide a power boat of the character indicated above in which maximum use is made of hull formation and power application to procure efficiency in expenditure of power for propelling the boat.

Other important objects of my invention will be apparent from a reading of the following description in connection with the drawings, wherein for purposes of illustration I have shown a preferred embodiment of my invention.

25 In the drawings:—

Figure 1 is a bottom plan view of the embodiment.

Figure 2 is a front end elevational view thereof.

Figure 3 is a longitudinal vertical sectional view 30 taken through Figure 1.

Figure 4 is a rear end elevational view.

Referring in detail to the drawings, the numeral 5 generally designates the hull which in plan outline may follow the accepted contour of a relatively sharp nosed squared sterned boat, but has the bow undercut as indicated by the numeral 6 so as to form a spoon-bow running from the forward extremity of the hull to the point 7.

Opposite sides of the bottom of the hull are 40 laterally inwardly curved as indicated by the numerals 8 and 9 and at points laterally displaced from the longitudinal center of the hull, the forward ends of the sides 8 and 9 and the longitudinal central part of the bow 6 providing chan- 45nels 10 and 11 which funnel the water into the tunnel 12 which runs rearwardly for the full length of the hull from the point 7 and opens through the stern 13 as indicated by the numeral 14.

50 The bow 6 has a centralized depending portion defined by the funnel formations 10 and 11 which is generally triangular in form and has laid therealong and secured thereto the metal keel 16 which runs all the way to the stern of the boat 55 where the keel 16 has a right angularly upwardly

projecting portion 17 which has bearing arms containing eyes 18 and 19 in which the rudder post 20 is swingably mounted to support the rudder 21 in proper position at the stern of the hull. A tiller 22 is attached to the upper end of the 5 rudder post.

Between the eye equipped arms 18 and 19 on the vertical portion 17 of the keel 16 is the bearing structure which is generally designated 23 which journals the rear end of the propeller 10 shaft 24 which has its front end journaled in the transverse partition 25 which rises from the point 7 and extends across the interior of the hull 5. The horizontal portion 26 of the keel 16 is spaced below the top of the water tunnel 12 and lies 15 along the longitudinal center of the hull.

The propeller shaft 24 has in front of the partition 25 and located in the space 27 which is defined by the partition 25 and the prow of the boat, the sprocket wheel 28 which is connected 20 with the sprocket wheel 29 which is located on the shaft 30 which has its front end supported in a bearing 31 on the top of the partition 25. The shaft 30 extends rearwardly through a supporting bearing 32 mounted on the floor 33 of 25 the hull and is operatively connected to the motor or engine 34; whereby the propeller shaft 24 is driven at the required speed and with the required power. Any suitable motor or engine 34 may be utilized. In order to bring the motor 30 down as low as possible so as not to have an over-balancing effect on the hull when in the water, the engine is set in a depressed position in a pit 35 in the floor structure 33.

The propeller shaft 24 has by preference spiral 35 continuous blade structure 36 which runs the length of the water tunnel and the length of the propeller shaft 24 between the partition 25 and the stern of the boat. The bearing structure 23 of the propeller shaft has a transverse brace ar- 40 arrangement 37 which is attached as indicated by the numerals 38 and 39 to opposite marginal portions of the stern 13, as shown in Figure 4, whereby to firmly brace the rear end of the propeller shaft and insure smooth running thereof as well 45 as bracing the rear end of the keel 16. It is obvious that the keel 16 not only armors the prow of the hull, but provides the protection for the propeller and the water tunnel, and at the same time acts as a supporting structure for not only 50 the rear end of the propeller shaft, but for the rudder, and braces the stern of the hull.

The funnels 10 and 11 chute the water forcibly into the water tunnel 12 and pack the water in said tunnel, so that the propeller blade structure 55

36 gets a more effective purchase upon the water, and drives the same in a whirling column forcibly rearwardly through the opening 14 at the stern of the hull, so as to forcibly and evenly propel 5 the hull through the water.

If desired a sprocket chain 40 may be trained over the wheels 28 and 29 so as to form a drive connection therebetween, instead of a direct toothed meshed drive.

10 Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. A power boat comprising a hull including a 20 bow having water directing funnels on its underside, said hull at its underside having a longitudinal water tunnel into the front end of which said funnels lead, said tunnel being open at its bottom and extending uniformly from said funnels to the stern of the boat, longitudinal water propeller means confined entirely within and along said water tunnel, and means on said hull for driving said propeller means, and a metallic keel running along said bow and along said hull 25 under and spaced from said water tunnel for protecting the propelling means therein, the opposite ends of the keel extending upwardly at the bow and the stern and secured to the deck of the boat.

35 2. A power boat comprising a hull including a bow having water directing funnels on its underside, said hull at its underside having a longitudinal water tunnel into the front end of which

said funnels lead, said tunnel being open at its bottom and extending uniformly from said funnels to the stern of the boat, longitudinal water propeller means confined entirely within and along said water tunnel, and means on said hull for driving said propeller means, and a metallic keel running along said bow and along said hull under and spaced from said water tunnel for protecting the propelling means therein, said keel having at its rear end an upstanding portion into the stern of the hull and including rudder supporting means, the opposite ends of the keel extending upwardly at the bow and the stern and secured to the deck of the boat. 5

3. A power boat comprising a hull including a 10 bow having water directing funnels on its underside, said hull at its underside having a longitudinal water tunnel into the front end of which said funnels lead, said tunnel being open at its bottom and extending uniformly from said funnels to the stern of the boat, longitudinal water propeller means confined entirely within and along said water tunnel, and means on said hull for driving said propeller means, and a metallic keel running along said bow and along said hull 15 under and spaced from said water tunnel for protecting the propelling means therein, said keel having at its rear end an upstanding portion into the stern of the hull and including rudder supporting means, the opposite ends of the keel extending upwardly at the bow and the stern and secured to the deck of the boat. 20
